UNITED STATES PATENT OFFICE.

FRED. W. MÜLLER, OF HOBOKEN, NEW JERSEY.

BOTTLE-FILLING APPARATUS.

1,384,537.

Specification of Letters Patent. Patented July 12, 1921.

Application filed October 21, 1919. Serial No. 332,246.

To all whom it may concern:

Be it known that I, FRED. W. MÜLLER, a citizen of the United States of America, residing at Hoboken, county of Hudson, State 5 of New Jersey, have invented certain new and useful Improvements in Bottle-Filling Apparatus, of which the following is a specification.

My invention relates generally to apparatus for filling bottles and more particularly applies to such apparatus when operating on a gas-charged liquid. In handling such liquid, which is usually charged with carbonic acid gas, it is customary to 10 maintain in the tank holding the liquid fed to the bottles, a counter pressure of carbonic acid gas to reduce as far as possible the loss of gas from the liquid itself, the object being to get the liquid into the bottles 15 with as high a gaseous content as possible. Usually this counter pressure of carbonic acid gas has been created by allowing a portion of the gas contained in the liquid to be liberated in and trapped in the bottling 20 tank when the same is first put into operation for the day or for any particular run.

The carbonated liquid is received from the carbonating apparatus under a pressure of approximately 60 pounds. It is necessary to reduce this pressure in the bottling 25 apparatus, as otherwise the bottles might be burst by the pressure and the fluid leak also through the joints of the connecting pipes. It is customary to reduce this pressure to approximately 20 pounds, by passing 30 the fluid through a pressure reducing valve as it enters the bottling tank. As a result, the liquid is violently agitated by being forced through the small passageways of 35 this valve, enters the bottling tank in a small jet of high velocity, and is generally subject to such violent agitation that a large part of its gaseous content escapes.

Each empty bottle of course contains air 40 at the moment it is connected to the tank for filling and this air must be displaced by the entering liquid and passed up into the space in the tank above the liquid level. As there is a constant increase in the volume 45 of this air in the tank, as bottle after bottle is filled and its contents transferred to the tank, it is necessary to have a blow-off valve through which the surplus air can escape at a predetermined counter-pressure of approximately 20 pounds to the square inch.

Heretofore this blow-off valve has been placed directly on or in the bottling tank itself and by its intermittent action it produces sudden and considerable variations in counter-pressure in the tank, and every time 60 the pressure drops suddenly as the result of the opening of the blow-off valve, there is a further tendency to liberate a considerable amount of the gases contained in the liquid, which mixes with the air from the bottles and blows off through the blow-off 65 safety valve.

My invention avoids these difficulties by employing a separate supply of gas to generate the counter-pressure on the initial 70 operation of the apparatus and delivering said gas to the particular zone in the tank which it would naturally seek by reason of its particular specific gravity, and by having the exhaust connection for the excess air 75 opening from that zone of the tank which the air would naturally seek by reason of its particular specific gravity, and then instead of placing the blow-off valve directly on or in the bottling tank, I place it on a 80 separate second tank of considerable capacity, and connect the blow-off pipe to this second tank, the pipe being of relatively small cross-section. Preferably also I connect, by a similar pipe, the gas zone of the 85 bottling tank with a corresponding zone of the second tank. The best form of apparatus at present known to me employing my invention is illustrated in the accompanying two sheets of drawings, in which— 90

Figure 1 is a side elevation and partial section of one standard form of bottle filling apparatus equipped with my invention;

Fig. 2 is an enlarged detail of the stuffing box system connecting the rotary parts of 95 the bottle filling apparatus with the rigid connections thereof;

Fig. 3 is a cross section on line 3—3 of Fig. 2;

Fig. 4 is a cross section on line 4—4, of 100 Fig. 2, and

Fig. 5 is a cross section on line 5—5 of Fig. 2.

Throughout the drawings like reference characters indicate like parts.

A represents generally the bottle filling apparatus which is of the rotary type having an annular or "doughnut-shaped" tank C, supported on a spider S, in which the liquid to be employed in filling the bottles 110

is contained. The carbonated liquid is supplied from any suitable source through the pipe X, which has a rotary stuffing box B' affording connection to the vertical section 5 of piping which is branched at X' and X' to deliver the liquid to the interior of the bottle filling tank C.

My present invention finds its most advantageous use when the liquid supplied 10 through pipe X, comes from a smaller equalizer tank, such as is shown in my pending application Serial No. 333,922, filed October 28, 1919, and is delivered to the bottling tank C without the intervention of any 15 pressure reducing valve. The tank and the usual bottle handling apparatus are supported on the central column D which rotates on the base Z, and on which column the spider S is mounted. The bottle handling apparatus as represented comprises the vertically movable bottle supports R, R, automatically raised and lowered by air pressure operating in cylinders P, P. The compressed air is supplied to these cylinders P, P, through the pipe Q which is rigid and connected to any suitable source of supply of compressed air and which communicates through rotary stuffing box B with the pipe Q' carried by the rotating portion 25 of the bottle filling apparatus and which in turn communicates with the circular conduit Q² from which branch connections to the cylinders P—P are made.

The air contained in each bottle escapes 30 to the upper part of the tank C, through pipe L, and the counter-pressure of gas is admitted through pipe 1, to the bottle to expel the air therefrom. The upper end of pipe 1 is below the normal upper boundary 35 of the gas zone in the tank C, while vent L discharges at or above said upper boundary of the gas zone, indicated in Fig. 1 by the broken line g.

The foregoing described apparatus is of 40 standard type and its operation need not be set out in detail further than to say that bottles placed upon the supports R are automatically lifted and connected with the liquid-containing zone of the tank C, so 45 that the air in said bottles may be discharged from them into the tank, through vent L, and a portion of the liquid in said tank flow down into the bottles and fill them.

50 In order to prevent the escape upon the initial operation of the apparatus, of an unnecessarily large amount of the carbonic acid gas or other gas with which the liquid is charged, I establish in the bottle filling tank C an initial counter-pressure of carbonic acid gas supplied from a separate source. In the present case this gas is supplied from reservoir K, through pressure-reducing valve E and pipe N', which connects with the outer sleeve J of the stuffing-

box system, shown in detail in Figs. 2 to 5. The sleeve J enters the rotating stuffing-box U, and that in turn connects with the branch pipe N, which revolves with and discharges into the interior of tank C, at a point F 70 slightly above the level of the liquid in said tank and below the normal upper boundary of the gas zone in said tank, indicated by the broken line g.

It is evident that as a series of bottles 75 are filled, there will be a considerable accumulation of air from said bottles, in tank C, which excess air must be gotten rid of to prevent the creation of an increased counter-pressure which would interfere with 80 the admission of further supplies of the carbonated liquid. Also any excess gas liberated from the liquid itself must be removed for the same reason. Heretofore it has been customary to place some kind of 85 a blow-off safety valve directly on or in the tank C, to allow this air and gas to blow off directly through this valve. This, however, as before explained, has resulted in violent and sudden fluctuations in the pressure in tank C, so that an unnecessarily large amount of gas has been liberated and blown off with the air. My invention overcomes 90 this difficulty by discharging the surplus air through a pipe M, of relatively small 95 cross-section, having its inlet at H, near the roof of tank C, at which point the air discharged from the bottles tends to collect. Pipe M, which of course revolves with the tank C, connects with the intermediate 100 sleeve I of the stuffing box system, and through it to the exterior stationary pipe M', which extends to the top of a separate tank T of relatively large capacity. The safety blow-off valve O is placed on the top 105 of this tank T. Pipe N' is also connected to tank T, preferably near the bottom thereof.

The stuffing box system necessary to connect the rotating branch pipes M, N, and 110 Q' with the rigid external pipes M', N', Q, comprises the following parts: the lower stuffing box B, carried on the standard G, extending upward from the rotating bottle filling apparatus, connects the vertical section of the stationary pipe Q with the rotating section Q'. The rotating stuffing box Y makes an air tight joint between the stationary pipe section Q and the rotating intermediate sleeve I to the interior of which 115 the pipes M, M', are connected. The rotating stuffing box U makes a tight joint with the stationary outer sleeve J, to which the stationary pipe N' is connected and this stuffing box U has its interior connected with 120 the rotating branch pipe N. The rotating stuffing box W makes an air tight connection between the upper portion of the stuffing box system to which the rigid pipe M' is connected and the rotating intermediate 125 130

sleeve I. The stationary stuffing box V makes an air tight connection between the pipe Q and the upper end of the stuffing box casing.

5 The operation of my invention when embodied in the apparatus above described is as follows:

The pressure reducing valve E is set to permit a flow of gas from reservoir K, to 10 establish the desired counter-pressure in the tanks C and T, which counter-pressure is usually 20 pounds to the square inch. The carbonated liquid enters through the pipe X, branches X' and X², to the bottle filling 15 tank C at said pressure or slightly above it, the level of liquid therein being determined by the amount of gas previously admitted. Thereafter there is no flow of gas from reservoir K, unless there is a leakage at the 20 pipe joints and stuffing boxes, in excess of the amount of air discharged from the bottles and of gas liberated from the liquid. As the liquid flows quietly into tank C, little of its contained gas is so liberated. The 25 tank and bottle handling apparatus are rotated by hand or power and the mouths of the bottles placed on the vertical reciprocating supports R are progressively placed in connection with the interior of the tank 30 C so that the air in each bottle is discharged into the tank and the liquid from the tank flows down into the bottle. The air so discharged into the tank being of less specific gravity than the carbonic acid gas therein 35 rises to the upper zone of the bottle filling tank C. The carbonic acid gas being considerably heavier than the air tends to stay in the lower zone where it was originally delivered from the liquid and from the nozzle F. Any carbonic acid gas liberated 40 from the liquid in the tank C mixes with the stratum of the carbonic gas immediately above the surface of the liquid.

As the air from the bottles is delivered to 45 tank C and compressed by the constantly inflowing body of liquid, this air is forced up through pipes M, M', into tank T, slightly compressing the gas originally in said tank T. When this increase of pressure becomes 50 sufficient to pop the safety valve O, the excess of air and such gas as may have become mixed with it, escapes through the safety valve. The previously described increase of pressure in the tank C has also 55 caused a portion of the gas in the gas zone thereof to be forced back through pipes N, N', to the lower portion of the second tank T. The result of this arrangement is to maintain a layer of gas, or of a mixture 60 in which the gas largely predominates, in contact with the liquid in the tank C, and to blow off the air from said tank without producing any violent fluctuations of the pressure therein. The fluctuations in pressure 65 sure produced by the intermittent action of

the blow-off safety valve O, are localized in the separate tank T, and are only slowly and gradually transmitted to the bottling tank C, by reason of the wire drawing of the gas and air through the pipes M', N', 70 of relatively small cross-section. If at any time so much leakage occurs in the stuffing box system, or through the joints of the apparatus, that the counter-pressure tends to fall below the predetermined amount, the 75 pressure reducing valve E opens and allows the necessary additional quantity of gas to flow into the system from the reservoir K.

A further advantage of my invention arises from the fact that the range of fluctuations of counter pressure in the bottle filling tank is much less as the blowoff valve O operates, from time to time, to discharge the accumulating air, when it is located on the tank T, as shown, than is the case when 80 the valve is on the bottling tank. Consequently there is less liability of the counter pressure falling below the point at which the reducing valve E opens to admit additional gas from reservoir K. Therefore the 85 consumption of carbonic acid gas from reservoir K is less during a given period of operation of my invention than is the case in the old arrangement. This I believe to be due to the fact that with the larger volume of gas and air contained in the two tanks as compared with that which would be contained in the tank C alone, if the additional tank T were not used, the fall of 90 pressure in the system when blowoff valve 100 O opens is slower and more gradual and said valve is given time to perform its closing function and check the outflow of gases before the counter pressure has reached a point much below the predetermined amount at 105 which the valve is set to close, whereas, if the volume of trapped gas and air were only the smaller amount contained in tank C alone, there would be a greater drop in pressure thereof produced by the outrush of the 110 same volume of the air and gas during an equal period of time before the valve O had a chance to react and close the discharge port.

Also the maintaining of a larger percentage of carbonic acid gas in contact with the surface of the liquid from which it is liberated, than would be the case where my invention is not used, is beneficial to the liquid, as said gas contains fewer impurities 115 than atmospheric air. This retaining of a blanket mainly composed of carbonic acid over the liquid is due to the blowoff connection being made to the upper part of tank C, to which upper portions of said tank 120 the air from the bottles is delivered, to the slow diffusion between gas given off by the liquid and the air liberated from the bottles, resulting from the relatively quiescent condition of the gaseous contents of the tank 130

resulting in turn from the above stated reduction of fluctuations in the counter pressure.

Having described my invention, I claim:

- 5 1. In an apparatus for filling bottles with a gas-charged liquid, the combination, with a tank partly filled with such liquid and means for connecting a bottle mouth with the liquid containing zone of said tank, of 10 a second tank of relatively considerable capacity, a pipe of relatively small cross-section leading therefrom to a point in the partly filled tank near the top thereof, and a blow-off valve connected to said second 15 tank.
2. A structure such as set out in claim 1, combined with a reservoir of gas under pressure, a connection therefrom to the gas zone of the first mentioned tank, and a pressure reducing valve in such connection.
3. In an apparatus for filling bottles with carbonated liquid, the combination, with a tank partly filled with such liquid and

means for connecting a bottle mouth with the liquid containing zone of said tank, of a 25 second tank, a conduit of relatively small cross-section leading from the upper portion of the second tank interior to the upper portion of the filling tank interior, a similar conduit leading from the lower portion of the second tank to a point in the filling tank interior slightly above the normal level of the liquid therein, and a blowoff valve connected to the upper portion of the second tank.

4. A structure such as set forth in claim 3, combined with a reservoir of gas under higher pressure than that designed to be maintained in the two tanks, a connection from said reservoir to the second conduit and a pressure reducing valve in said connection.

FRED. W. MÜLLER.
